LLOYD M. WILLIAMS AND PERCY J. WILLIAMS, OF SAN FRANCISCO, CALIFORNIA.

DESIGN FOR AN ACCELERATOR PEDAL.

Application filed September 1, 1926. Serial No. 18,932. Term of patent 3½ years.

To all whom it may concern:

Be it known that we, LLOYD M. WILLIAMS and PERCY J. WILLIAMS, citizens of the United States, residing at San Francisco, in the county of San Francisco, State of California, have invented a new, original, and ornamental Design for Accelerator Pedals, of which the following is a specification, reference being had to the accompanying drawing, forming part thereof.

Fig. 1 is a perspective view of an accelerator pedal showing our new design.

Fig. 2 is a side elevation of an accelerator pedal showing our new design.

Fig. 3 is a top plan view of an accelerator pedal showing our new design.

We claim:

The ornamental design for an accelerator pedal, as shown.

LLOYD M. WILLIAMS.
